UNITED STATES PATENT OFFICE.

ALFRED LESSARD, OF WASHINGTON, DISTRICT OF COLUMBIA.

TAG HOLDER.

Application filed May 25, 1922. Serial No. 563,657.

To all whom it may concern:

Be it known that I, ALFRED LESSARD, a citizen of the United States, residing at the city of Washington, in the District of Columbia, 5 have invented certain new and useful Improvements in Tag Holders, of which the following is a specification.

This invention relates to holders for tags, chiefly used in shoe factories to indicate different 10 grades of shoes; and it consists in the novel construction and combination of the parts hereinafter fully described and claimed.

In the drawings, Figure 1 is a side view 15 of a tag holder constructed according to this invention. Fig. 2 is a plan view of the same.

A supporting stem 4 is provided having a screwthreaded lower end portion 5 adapted to be screwed into a shelf or case containing 20 the goods. The upper end portion 6 of this stem is also preferably screwthreaded, and 7 is a tubular socket which is screwed onto the part 6. A hook 8 provided with a screwthreaded shank 9 is screwed into a hole 25 formed crosswise in the socket, and bears against the part 6 so that the socket 7 is locked to the stem 4.

Any approved form of price tag 10 or other similar device is hung on the hook 8, 30 and can be removed and replaced as often as desirable. A flag 12 is provided, and it has a staff 14 which is screwed into the upper end portion of the socket 7, and can be removed and replaced as often as desirable.

The flag is preferably formed of thin sheet 35 metal, and it carries any suitable announcement, such as the day of the week. Flags having different names or dates can be substituted one for another without removing the supporting stem or the tag, and a set of 40 suitable flags is provided for use with a series of stems in different parts of the factory.

What I claim is:

1. A tag holder, comprising a supporting stem, a socket carried by the said stem, a support for a tag attached to the said socket, and a removable flag provided with a staff 45 for engaging with the said socket and being removable therefrom without disturbing the support for the tag.

2. A tag holder, comprising a supporting stem, a tubular socket carried by the said stem, a support for a tag having a screwthreaded shank which engages with a lateral hole in the socket and locks it on the said 55 stem, and a removable flag provided with a staff which engages with the said socket.

3. A tag holder, comprising a supporting stem, a tubular screwthreaded socket screwed onto the upper end portion of the said stem, 60 means for supporting a tag also carried by the said stem, and a removable flag provided with a staff which is screwed into the said socket in line with the said stem.

In testimony whereof I have affixed my 65 signature.

ALFRED LESSARD.
